212,460

JAR OR SIMILAR ARTICLE

Floyd E. Pettengill, 1328 E. Fair Ave.,
Lancaster, Ohio 43130

Original design application Sept. 23, 1966, Ser. No.
3,990. Divided and this application Dec. 13, 1967,
Ser. No. 9,757

Term of patent 14 years

(Cl. D9—92)

Fig. 1.

Fig. 2.

FIG. 1 is an elevational view of a jar or similar article showing my new design; and

FIG. 2 is a sectional view taken along line 2—2 of FIG. 1.

The dominant features of my design reside in the portions shown in full lines.

The present application is a division of co-pending United States design patent application Ser. No. 3,990, filed Sept. 23, 1966.

I claim:

The ornamental design for a jar or similar article, substantially as shown and described.

UNITED STATES PATENT OFFICE
CERTIFICATE OF CORRECTION

Design No. 212,460

October 22, 1968

Floyd E. Pettengill

It is certified that error appears in the above identified patent and that said Letters Patent are hereby corrected as shown below:

In the grant, lines 1 to 3, for "Floyd E. Pettengill, of Lancaster, Ohio" should read -- Floyd E. Pettengill, of Lancaster, Ohio, assignor to Anchor Hocking Glass Corporation, of Lancaster, Ohio, a corporation of Delaware, --; line 13, "Floyd E. Pettengill, his heirs" should read -- Anchor Hocking Glass Corporation, its successors --. In the heading to the drawing and printed specification, lines 3 and 4, "Floyd E. Pettengill, 1328 E. Fair Ave., Lancaster, Ohio 43130" should read -- Floyd E. Pettengill, Lancaster, Ohio, assignor to Anchor Hocking Glass Corporation, Lancaster, Ohio, a corporation of Delaware --.

Signed and sealed this 16th day of December 1969.

(SEAL)
